UNITED STATES PATENT OFFICE.

WILLIAM A. ODENDAHL, OF DENVER, COLORADO.

COOLING RADIATOR.

Application filed December 17, 1923. Serial No. 681,159.

To all whom it may concern:

Be it known that I, WILLIAM A. ODENDAHL, a citizen of the United States of America, and resident of the city and county 5 of Denver, Colorado, have invented a new and useful Cooling Radiator, of which the following is a specification.

An object of this invention is to provide an improved construction for cooling radiators adapted for use on automobiles for the purpose of cooling liquid employed to prevent overheating of a gasoline motor used to drive the same.

A further object of this invention is to 15 provide improved means for facilitating assembling, dismounting, separation and repair of the parts of a cooling radiator.

A further object of this invention is to provide an improved construction for several of the parts of a cooling radiator.

My invention consists in the construction, arrangement and combination of elements hereinafter set forth, pointed out in the claims and illustrated by the accompanying 25 drawing, in which—

Figure 1 is a front elevation and Figure 2 a side elevation of a radiator embodying my improvements, the shell being omitted. Figure 3 is a horizontal section, on an enlarged scale, on the indicated line 3—3 of 30 Figure 1. Figure 4 is a detail perspective illustrating one form of construction and arrangement of end bars, fins and struts employed in the device. Figure 5 is a vertical section through a part of the radiator core further illustrating the structure shown in 35 Figure 4.

Figure 6 is a detail perspective showing a modified construction for the fins, whereby 40 a part of each fin constitutes a strut or support for a superposed fin.

Figures 7 and 8 are vertical sections and plan respectively illustrating various forms 45 of connecting radiator tubes to a tank header.

In the construction of the radiator as shown the numeral 10 designates a bottom tank, 11 an upper tank, 12 each of a series of vertical tubes connecting, communicating 50 with and spacing apart the tanks 10 and 11, 13 an outlet pipe for the bottom tank and 14 an inlet pipe for the upper tank; said upper tank also being provided with a filling nipple 15 at the center of its top. In a general 55 way the tanks and tubes are constructed in a common and well known manner and are

not involved in this invention except as a foundation for the other elements and as hereinafter described. In Figures 7 and 8 a tank header 16 is shown formed with holes 60 therethrough adapted to receive one end each of tubes 12. The holes in the header are reamed out and tapped at one end and glands 18, 19, 20, or various forms, are mounted loosely on the several tubes and are adapted 65 to be screwed into the tapped portions of the holes in the header and, at their inner ends engage gaskets 21 and seal the joints between the tubes and header. The gland 18 is formed with a tapered inner end opposed to 70 a tapered bottom of the reamed out portion of the appertaining hole and the gasket 21 therein is located between said tapered end and bottom. The gland 18 also is otherwise cylindrical and is formed with notches 75 22 in its outer end adapted to be engaged by a spanner for operation of the gland, either for seating or unseating thereof. The tapered end of the gland 18 and tapered bottom opposed thereto are sphere-shaped. 80 The gland 19 is formed with a frustum shaped inner end opposed to a frustum shaped bottom of the reamed out portion of the appertaining hole in the header and the gasket 21 therein is located between said 85 end and bottom. The gland 19 also is formed with a nut 23 on its outer end adapted to be engaged by a wrench for operation of the gland, either for seating or unseating thereof. The gland 20 is formed 90 with a flat inner end opposed to a flat bottom of the reamed out portion of the appertaining hole in the header and the gasket 21 therein is located between said end and bottom. The gland 20 also is formed with a 95 nut 23 on its outer end adapted to be engaged by a wrench for operation of the gland, either for seating or unseating thereof. The header 16 may constitute the top of the tank 10 or the bottom of the tank 11, 100 and is of material and considerable thickness to accommodate the reamed and tapped holes. The gaskets 21, under compression of the glands, provide and maintain frictional engagement with the tubes 12 sufficient 105 to keep said tubes in proper relation with the tanks, thus providing means for conveniently assembling, or removing any tube for repair or substitution.

The core of the radiator is built up and 110 filled in of two sets or series of fins 24, 25, all of which fins are alike in form and

construction and are interchangeably usable. Each set or series of fins 24, 25 is connected with and carried by end bars 26, 27 and 28, 29, two for each set or series, and said end bars are of like form and construction, except as to fastening means, and are substantially interchangeably usable. The end bars are adapted to be mounted in pairs between end portions of the tanks 10, 11 as shown. The fins 24, 25, are each formed of thin sheet metal with a fold or roll 30, 30 on its outermost long margin and is formed with outwardly-opening notches 31, extending thru the fold or roll and of a width corresponding to the thickness of and adapted to receive the end bars 26, 27, 28, 29 respectively. The notches 31 extend throughout somewhat more than half the width of each fin. The end bars 26, 27, 28 and 29 are formed with inwardly-opening notches 32, one for each fin of the respective series, and said notches extend throughout substantially half the width of the bars and are adapted to receive those portions of the fins at the inner ends of the notches 31. Thus the fins and end bars are halved together for assembling in sets and they may be connected by a drop of solder 33 at the outer end of each fin. Because of this arrangement and connection of the end bars and fins, each set, front and rear, thereof may be placed, removed and replaced independent of the other, and when assembled as shown the inner margins of the fins are spaced apart slightly. The fins 24, 25 are formed with inwardly-opening notches 34, 35 adapted to receive parallel tubes 12 and permit free circulation of air between the tubes and between and through the fins adjacent to the tubes when the fins are assembled as shown in Figure 3. These notches 34, 35 also permit the sets of fins to be withdrawn from the tubes by lateral manual movement of the end bars. Struts, spacers or supports 36, 37 are formed of thin sheet metal with folds or rolls 38 on their inner margins and said struts are formed with outwardly-opening notches 39, 40 adapted to receive portions of the fins 24, 25, said fins, in turn, being formed with inwardly-opening notches 41, 42 adapted to receive those portions of the struts at the inner ends of the notches 39, 40. The struts are arranged vertically between transverse rows of the tubes 12 and frictionally engage the fins, or they may be secured to the fins by drops of solder 43, so that said struts may be removed and replaced with the sets or series of fins in lateral manual movement of the end bars. Aperuted ears 44, 45 are fixed to the outer surface of inner marginal portions of the end bars 26, 27, 28 and 29, in sets near the upper and lower ends of said bars, and when the parts are assembled as shown said ears register vertically on opposite sides of the radiator and are con-

nected in sets by pins 46 adapted for manual removal and replacement. The interengaging pins and ears provide a convenient means of connecting the end bars in pairs on opposite sides of the radiator and through 70 said end bars, for connecting the sets of fins and struts on opposite sides of the median line of the radiator.

Upon removing all the pins 46, the end bars, fins and struts may be removed forwardly and rearwardly from the tubes 12, which done access is had to any tube for the repair, removal or replacement thereof. Or, under the same conditions, any strut or fin may be removed or repaired. 75

After any repair or renewal is made the sets of series of end bars, fins and struts may be replaced relative to the tubes 12 and reconnected by the pins 46 in intimate and stable relation to the tubes. When assembled as shown, the struts support the interior portions of the fins in proper spaced relation, and said struts and fins divide the air, forced by fan not shown, in passing through the radiator and about the tubes, also permitting the air to circulate freely up and down and around the tubes, thus applying the cooling air intimately and freely to the tubes. In Figure 5 both the fins 24, 25 and struts 36, 37 are shown contacting on the median line of the radiator. 80

In Figure 6, the struts as separate entities are omitted, and the fins 24', 25' are formed with recurved integral lugs 36', 37' extending upwardly therefrom in the locations otherwise occupied by the struts. The lugs on each fin engage and support the fin above it, and said lugs have substantially the same function as the struts in supporting, spacing and bracing the fins and in operating with said fins to divide the air passing through the radiator. 90

I claim as my invention—

1. In a radiator having upper and lower tanks and open-ended tubes connecting and communicating between said tanks, the combination therewith of banks or series of fins for the front and rear of said radiator, said fins being notched to admit said tubes and substantially meeting on the median line of the bank of tubes, end bars notched on their inner margins to receive said fins, said fins being notched on their outer margins to receive said end bars, said end bars being arranged transversely of said fins and removable and replaceable in series therewith relative to said tubes, and means for detachably connecting said end bars. 100

2. In a radiator having a bank of tubes, the combination therewith of two banks of fins for the front and rear of the radiator respectively, said fins being notched to receive the tubes and substantially meeting on the median line of the radiator, said fins having folds on their outer long margins, 110

- end bars notched on their inner margins to receive said fins, said fins being notched on their outer margins through said folds to receive said end bars, said end bars being arranged transversely of said fins and removable and replaceable in series relative to said tubes, overlapping ears on said end bars and removable pins in and connecting said ears.
3. In a radiator having a bank of tubes, the combination therewith of two banks of fins for the front and rear of the radiator respectively, said fins being notched to receive the tubes and adapted to be spaced apart at their inner margins, and struts formed with folds on their inner margins and notched on their outer margins to receive said fins, said fins being notched on their inner margins, between the tube notches, to receive said struts, said fins and struts being removable and replaceable together relative to the tubes.
4. In a radiator having a bank of tubes,
- the combination therewith of two banks of fins for the front and rear of the radiator respectively, said fins being adapted to be spaced apart and notched on their inner margins to receive said tubes, struts notched on their outer margins to receive said fins, said fins being notched on the inner margins between the tube notches to receive said struts, and end bars notched on their inner margins to receive said fins, said fins being notched on their outer margins outside of the series of other notches to receive said end bars, means for connecting said fins and struts and means for connecting said fins and end bars, whereby the separate banks of fins, the struts and the end bars are removable and replaceable relative to the tubes.

Signed at Denver, in the county of Denver and State of Colorado, this fifth day of December, 1923.

WILLIAM A. ODENDAHL.
